TYPEWRITING MACHINE

Harry C. Yaeger, West Hartford, Conn., assignor
to Underwood Elliott Fisher Company, New
York, N. Y., a corporation of Delaware

Application December 31, 1942, Serial No. 470,868

10 Claims. (Cl. 197—17)

This invention relates to typewriting machines embodying power typing and power carriage returning instrumentalities, and with regard to certain more specific features thereof, to devices preventing power typing at line ends, and also to devices preventing typing and certain other operations during carriage returns.

The stroke of the type keys in power typing machines is preferably very short and the touch is light. Furthermore, the release of the type keys is independent of the return of the typing instrumentalities, so that an operated type key is apt to be held depressed while another one is being operated. For the above and other reasons, the conventional key lever line end locks used in manually operated typewriters are unsuitable for use in machines embodying power-driven typing instrumentalities.

Accordingly, it is an object of the invention to provide, for use in a power typing machine, a reliably operative, simple device to prevent power typing following the movement of the typewriter carriage beyond a certain line end position.

Another object of the invention is to provide a device of the above nature which is normally non-impeding to the operation of the type keys.

In the machine of the present invention, the type actions are actuated by individual actuating mechanisms which are selectively power-operable under control of type keys. After giving a typing impulse to its associated type action, each actuating mechanism returns to its normal position independently of whether or not the associated type key has been released. In association with typing instrumentalities of this kind, it is a further object of the invention to provide reliably operative devices which unfailingly prevent power operation of the actuating mechanisms in response to a certain line-end carriage-feed-movement, despite the fact that the last operated type key, operation of which resulted in the line-end carriage-feed-movement, may be lingered upon by the typist.

Also, an object of the invention is to provide, in combination with power typing instrumentalities, means to prevent, in an efficient manner, typing and other operations during power carriage-returns.

Another object is to provide simple, unfailingly effective, devices to prevent power typing subsequent to the feeding of the carriage beyond a certain line end position, and to prevent power typing, and such operations as back spacing, while the carriage is being returned.

It is a further object of the invention to attain

the last-mentioned object in such manner that the type keys are normally freely operable, that is, without any encumbrance to the touch of the type keys.

5 Also, an object is to contrive efficient and reliably operative means to prevent power typing and other operations during carriage returns, such devices being of a nature allowing the type keys to be operated normally without hindrance, and normally further allowing carriage returns and said other operations to be effected only one after another.

With these and other objects in view, the invention includes certain novel features of construction and combination of elements, the elements of which are set forth in the appended claims, and a preferred form or embodiment of which is hereinafter described with reference to the drawings which accompany and form part of this specification.

20 In the accompanying drawings:

Figure 1 is a skeleton front perspective view of certain frame supported elements of a typewriting machine, including power typing instrumentalities and a line end lock therefor, and also including certain key controls for back spacing, tabulating, and other operations, together with an interlocking mechanism therefor.

Figure 2 is a front perspective view of a typewriter machine carriage together with a margin stop mechanism and portions of a power line spacing and carriage returning mechanism. The figure includes some of the mechanism shown in Figure 1 and may be conveniently read in conjunction therewith.

Figure 3 is a sectional side elevation depicting a type action as having been partly power actuated and continuing to print by momentum, independently of an already returning power actuating mechanism therefor, the returning power actuating mechanism giving operating clearance to an actuator lock slide.

Figure 4 is a front perspective and shows the lock slide of Figure 3 moved to effective position under control of a line end defining margin stop mechanism.

Figure 5 is a sectional side elevation substantially through the middle of the typewriting machine and shows principally the power typing and the carriage feeding mechanism, all parts being in their normal positions.

Figure 6 is a fragmentary front elevation of the machine with a power carriage return in progress and certain elements locked against operation.

Figure 7 is a schematic front elevation of a modified form of the key interlocking mechanism mentioned in connection with Figure 1.

Directing attention now more particularly to Figs. 1 and 5, the machine frame is designated by the reference character 10 and comprises two spaced side-walls 11. As seen in Fig. 5, a carriage 12 is guided for letter-feed and return movements in the conventional manner upon a track-way 13 which forms part of the machine frame 10. The carriage has opposite end pieces 14 wherein a platen 15 is rotatably supported. A spring motor (not shown) letter-feeds the carriage 12 under control of an escapement mechanism generally designated by the numeral 16, in response to each typing operation, in a manner to be described later.

The illustrated power typing instrumentalities are substantially the same as shown and described in the Patent to Yaeger No. 2,254,764, dated September 2, 1941, and may comprise a multiplicity of type actions, each comprising a pivoted type bar 17 operable by a lever 18 through a connecting link 20, the levers being pivoted on a common straight pivot rod 21 and being normally urged to their normal positions by springs 22. The type-bars are pivotally supported in an arcuate array upon a segment 18 and are movable to strike the platen at a common printing point. Each type action has associated therewith an actuating mechanism 23 comprising, a pendant arm 24 in rolling contact with the lever 18, and an actuating link 25 articulated and extending rearwardly from the arm 24. Springs 26 urge the actuator links, together with their associated arms 24, upwardly and rearwardly, each to occupy normally a position as seen in Fig. 5, the arms 24 being then in motion limiting engagement with a framework cross member 28 in slots 27 whereof the pendant arms 24 are pivotally supported on a pivot wire 29. At the rear, the actuator links normally contact a horizontal face of an elongate plate 30 having a rearwardly and downwardly bent portion 31 provided with slots 32 wherein the rear ends of the actuator links 25 are guided in vertical fore-and-aft extending planes. Each actuator link 25 has pivoted thereon near its rear end a snatch pawl 33 which is adapted to be brought into engagement with a continuously revolving power drive member or snatch roll 34, by drawing the actuator link 25 downwardly about its point of articulation with the pendant arm 24. To effect such downward drawing of the actuator links, there is associated with each actuator link 25 a type-key lever 35 provided with an upright member 36 having a hook end overlying a lug 37 on the actuator link. Preferably, the manner in which the hook members 36 are carried by the type-key levers is such, that the former may yield upon the latter in a forward as well as in an upward direction for purposes well known. When a snatch pawl has been lowered into engagement with the snatch roll 34, the latter first causes the snatch pawl 33 to revolve limitedly about its pivot and thereafter drives the snatch pawl, together with the associated actuator link forwardly to operate the associated type action. Some time prior to the type bar 17 striking the platen 15, a cam face 38 on the actuator link 25 engages an abutment device 41, thereby causing the operated actuator to be deflected upwardly and the snatch pawl to be disengaged from the snatch roll. It will be perceived that the actuator

mechanism 24, 25 thereupon returns immediately to normal position, whereas the type action proceeds to type by momentum stored therein, and thereafter returns under the tension of its spring 22. Furthermore, an actuator 25, as soon as the pawl 33 is forced clear of the roll 34, will be drawn against the plate 30 by the spring 26 and will glide to normal position while remaining in contact with said plate.

10 The keys 35 pivot about a common fulcrum rod 53 which is embedded in a bar 54 of the machine frame, the bar being slotted to accommodate the rear ends of the keys. At the front, the key levers 35 are guided in slots 49 of a comb plate 50, to the upper limits of which slots they are normally urged by springs 55 which are connected to the key levers slightly in front of the pivot rod 54. When the operated type bar approaches the platen, a universal bar 42, see Fig. 5, is contacted and driven rearwardly to actuate the aforementioned escapement mechanism 16. The connections from the universal bar to the escapement mechanism include a rocker frame 43, and a link 44 connecting the rocker frame with the said escapement mechanism. The latter may consist of a pivoted unit 45 carrying two conventional escapement dogs 46, one of which is normally in engagement with the escapement wheel 47 and prevents the carriage from moving. The escapement wheel 47 is fixed on an escapement wheel shaft 48 which also has fixed thereon a gear 51 meshing with a carriage supported rack 52. It may thus be understood that the carriage letter-feed in response to each operation of the universal bar 42, just after the type bar 17 strikes the platen, and, since the actuator becomes disconnected from the power roll 34 prior, it follows that the carriage letter-feeds always after the restoring elevation of the actuator link 25 against the plate 30, substantially as illustrated in Fig. 3. The lug 37 on each actuator link, upon the return of the latter, will assume an inoperative position with respect to its hook member as long as the key controlling the hook member is held depressed. More specifically, pending release of the key 35, the lug will idly displace the hook member rearwardly about its pivot pin 56 by engaging the hook member above its hook face. Upon release of the key, the hook member will assume its normal operative position over the lug 37.

Word spacing movements of the carriage occur through an actuator similar to the actuators 25, this actuator being adapted to operate the escapement 16 through an operating connection, under the control of a space key, in a manner not shown.

The carriage ends 14 mount a rack 57, along which are adjustably locatable margin stops 58, 59 defining, respectively, the limits to which the carriage may be advanced and returned.

Pivoted as at 62, Figs. 1, 4 and 6, to a part of the framework is an upright counterstop arm 64 having normally a stop finger 65 disposed between and in the path of the margin stops 58, 59, said finger projecting through an opening 66 in a horizontal plate 67 secured to a column 68 forming part of the framework 10. The arm 64 is slotted at its pivotal point 62 so that it may be lowered to dispose the stop finger 65 below the margin stops 58, 59, a spring 72 being provided to cause the arm to pivot normally with the lower end of the slot abutting the pivot pin, the spring being additionally urging the finger

end 65 against the right end of the opening 66. During the advance of the carriage as the carriage approaches the traveling limit as defined by the margin stop 58, the latter engages the finger 65 and causes leftward displacement of the arm 64. This occurs during the last possible letter-feed movement of the carriage as illustrated in Fig. 4, and causes an actuation of a toothed line-end lock slide 73 to an effective position blocking the actuators 25 against being drawn downwardly into operative relation with the snatch roll 34. The lock slide has teeth 74 which are normally situated between the rear ends of the actuator links 25 and which, upon actuation of the slide, will underlie and block them against being drawn down by the hook members 36. The slide is slidably accommodated on top of the bar 54 and for this purpose is provided with slots 75 wherein there are headed guiding screws 16 supported by the bar. The arm 64 operates the slide through a yielding connection comprising a lever 77 and an arm 78, both pivoted to the machine framework by a common pin 81. A spring 82 urges the lever 77 and the arm 78 toward each other with the arm 64 therebetween. Under normal conditions, the arm 64, when actuated by the margin stop 58, will displace the lever 77 and the arm 78 unitarily, but should the slide 73 be obstructed in its movement, the arm 78 will be operated without enforcing movement of the lever 77, thereby avoiding damage to the mechanism. Such idle movement of the arm 78, for example, may occur when moving the carriage manually while substantially concomitantly also operating a type key.

It has been explained that the carriage letter-feeds after disengagement of a last-actuated actuator 25, that is, after such actuator has been elevated clear of the power roll 34, into engagement with the plate 30. It will thus be seen that the returning actuator allows unobstructed movement of the lock slide 73 to effective position, that is, to the position wherein its teeth 74 are posed underneath the rear ends of the actuators 25, see Fig. 3. The clearances between the slide teeth 74 are only slightly wider than the rear ends of the actuator links, wherefore, the teeth 74 will block the actuators 25 practically immediately after the final line-end letter-feeding movement has started. This, it will be noted, is at the beginning of the retreat of the type bar from the platen, amply before even an untrained typist would be likely to operate the next type key. The lock slide 73, therefore, moves unfailingly to effective position regardless of whether an operator may linger on a last-operated key.

Should it be desired to type beyond the margin defined by the margin stop 58, the operator may depress a margin release key 83, which, through a lever 84 overlying a pin 85 on the counterstop arm 64, is effective to lower the latter below the margin stop 58, the finger 65 being then, under the tension of the spring 72 temporarily assuming a position underneath the stop 58. The margin release key 83 may also be used in similar manner to allow movement of the carriage in carriage-return direction beyond the position defined by the carriage return stop 58.

The power mechanism for returning the carriage and line-spacing, as also the controlling mechanism therefore, may be substantially the same as shown and described in the patent to Helmond No. 2,262,676, dated November 11, 1941,

and will now be described briefly as far as is necessary for an understanding of the invention.

A preferably continuously operating electric motor 86, disposed at the left rear portion of the machine, see Fig. 1, drives a pinion shaft 87 of which the pinion meshes a gear 88 fixedly carried on a spindle 91. The shaft 87 revolves near its pinion end in a frame-supported housing 92 which also provides journals for the spindle 91. A drum 93 normally free to rotate on the spindle 91 has a draw band 94 attached thereto in a manner to be wound thereon when the pulley is rotated counterclockwise of Fig. 1. During use of the machine, the motor 86 rotates the gear 88 and spindle 91 continuously, but the drum 93 remains normally stationary. Said gear 88 has clutch teeth 95, and the drum 93 has splined thereto, in a manner not shown, a toothed clutch collar 96 which is rotatably loose on the spindle 91, but axially movable thereon from an open clutch position to a position in which it is clutched to the gear 88. A rock shaft 97, journaled in the casing 92, has fixed thereto a yoke 98 fitting a groove in the clutch collar 96 and an operating arm 101, fixed to the shaft 97, serves to rock the latter together with its yoke to move the clutch collar 96 to close and open the clutch. The draw band 94 passes over frame-supported guide pulleys 102, 103, onto a pulley 104 journaled on the left carriage end 14, and has an end so attached and wound around the pulley 104 that rightward pull of the draw band rotates this pulley clockwise. A bevel pinion 105 is fixed to and rotatable together with said pulley 104 and meshes with a gear sector 106 pivoted on the left carriage end 14. Said sector 106 is integral with a cam 107 adapted to actuate through the medium of a roll 109 a spring-retumed line-space lever 108 carrying a line-space pawl 111, the latter, when actuated, being effective to feed a toothed platen-rotating wheel 112. Upon a rightward pull of the draw band 94, that is when the clutch member 96 is in engagement with the clutch teeth 95, the gear sector 106 is rotated limitedly and causes an actuation of the line-space pawl 111. When the clutch 95, 96 is opened as will be explained hereinafter, a spring 113 returns the sector 106 to normal position against a stop 110 and thereby causes some of the draw band 94 to be wound back onto the pulley 104. To keep the draw band 94 taut at all times, the drum 93 is under constant tension of a draw band winding spring, not shown, contained in a spring barrel 114 and being lighter than the spring 113.

Connected to the arm 101 by a link 116 is an arm 117 of a lever 118, the latter of which is pivoted at 121 to a rear wall of the aforesaid column 68. The rightward extreme of the arm 117, as seen in Fig. 1, is normally engaged by a latch 122 which is pivoted to the outer side of the right side wall 11 of the machine by a headed pin 119. With said lever arm 117 thus latched, a spring 115 is normally restrained from moving the arm 101 and closing the carriage return clutch 95, 98. A pivoted, spring-restored carriage-return key lever 123, when operated by depression of its key, elevates a pin 124 on its rear end and swings the latch 122 free of the right end of the arm 117, and thus causes closure of the clutch 95, 98 under the urge of the spring 115. The drum 93 being then consequently motor-driven, drives the carriage-carried pulley 104 so that an actuation of the line spacing mechanism 106, 111 ensues. After a limited rota-

tive movement of the pulley 104, the band 94 picks up the carriage to effect its return.

As the carriage reaches the position defined by the carriage return stop 59, the lever 118 is automatically restored and the clutch 85, 96 consequently opened, in a manner to be described presently. As illustrated in Fig. 6, the lever 118 includes an upright arm 125 to which there is pivoted a transverse link 126, which in turn is pivoted at 127 to another transverse link 128, said links forming a toggle. The link 128 is guided near its left end in a vertical slot provided in a wall of the column 68 and rests upon a lug or shelf 131. The link 128 has a stud 132 passing into a slot 133 of a link 134 connecting the counter-stop arm 64 with the link 128, the link 134 leaving the arm 64 always free to be moved downwardly under the control of said margin release key 83.

Assuming the carriage 12 to be in an intermediate position as shown in Fig. 2, the toggle 126, 128 is almost straight, but upon the release of the lever 118 from the latch 122, the toggle will be flexed upwardly, the stud 132 of the toggle link 128 being then reacting against the left end of the slot 133 in the link 134, but the latter and the counterstop arm 64 remaining unmoved, in substantially the position of Fig. 2, under the tension of the spring 72. Posed over a nose 135 of the toggle link 128 and being coextensive with the length of the carriage, is a control bar 136, mounted for downward diagonal movement on the carriage, against the tension of a spring 137, the bar being provided at opposite ends with diagonal slots 138, whereto there extend mounting pins 141 projecting from a part of the carriage framework. As the pulley 104 is being rotated by the draw band 94, incidental to line-spacing, as hereinbefore stated, a pin 142 engages a hook-shaped end 143 of the control bar 136 to displace the latter diagonally downwardly. The result is that the bar 136 pressed down on the nose 135 so that the toggle 126, 128 becomes almost straightened and the counterstop arm 64 is displaced leftwardly by the link 134 in opposition to the spring 72, the spring 115 being stronger than the spring 72. There being nothing opposing the rightward travel of the carriage, the band 94, after actuating the line-spacing mechanism, draws the carriage rightwardly until the margin stop 59 engages and moves the counterstop 64 against the right end of the opening 66, whereby the toggle is moved bodily to the right, it being understood that the lowered control bar 136 meanwhile opposes upward flexing of the toggle. This action results in the restoration of the lever 118 and, consequently, in a clutch opening movement of the yoke 88, the carriage return operation being thus automatically brought to a conclusion. If, meanwhile, the carriage return key 123 has been released, the lever 118 will be relatched by the latch 122. On the other hand, if the operator has not yet released the carriage return key 123, a secondary latch 144, also pivotally carried on the left side wall 11 by this pin 118, will hold the lever 118 in open clutch position pending the release of the key 123, see Fig. 1. The latches 122 and 144 have arms engaging the pin 124 at opposite sides and are yieldingly urged into contact with said pin by a common spring 145. Consequently, the latches 122, 144 are alternatively urged to effective positions by the spring 145, under the controlling influence of the key 123.

From the above it will be seen that an actua-

tion of the control bar 136, as well as a rightward movement of the margin counterstop 64, is required for effecting a clutch opening movement of the lever 118. Should the carriage already be in the extreme returned position at the time the carriage return key 123 is depressed, the lever 118, upon being tripped, will flex the toggle 126, 128 upwardly; and, the counterstop arm being then in its rightward position, the operation of the line spacing mechanism alone, with the accompanying depression of the control bar 136, will cause the restoration of the lever 118 to open clutch position. The pin and slot connection 132, 134 between the link 134 and the toggle allows full operation of the counterstop arm 64 by the line-end margin stop 58, even though the trip lever 118 may be in its normal, latched position, as may be realized from Fig. 2.

It will be remembered that the counterstop arm 64 moves leftwardly in consequence of the actuation of the control bar 136, provided, however, that the carriage is not in its returned position. Therefore, since leftward movement of the arm 64, as brought out before, causes an immediate movement of the slide to actuator-blocking position, it follows that the power typing instrumentalities will be positively and unfailingly locked against operation during the entire return movement of the carriage, see Fig. 6 in which in which the carriage is being power returned.

Referring now particularly to Figs. 1 and 6, the carriage return key lever 123 is fulcrumed on the pivot rod 53 and is guided similarly to the type key levers 35 in a slot provided in the bar 64. In like manner, mounted directly adjacent to the carriage return lever 123 is a lever 146 which has a forward end 147 adapted to enter between an abutment 148 and one of a series of blocks 151 and 152 disposed adjacently between the said abutment and another abutment 153, the latter being at the left end of the keyboard. The blocks 151 are shown to be in the form of rolls, whereas the block 152 comprises a bar which is nearly coextensive with the breadth of the keyboard, all the blocks being supported for lateral movement on a straight face 154 afforded by an incompletely shown cage, generally designated by the reference character 155, including also the said abutments 148 and 153. By reason of the carriage return lever 123 having a pin 159 overlying the lever 146, the latter lever becomes operated upon depression of the former and causes the blocks 151, 152 to be crowded or compacted leftwardly against said abutment 153. This crowding of the blocks obstructs certain parts in the machine against operation, whereby such operations as back spacing, tabulating, and tabulator stop setting are prevented. More specifically, the crowding of the blocks 151, 152 render inoperable the control keys for such operations. Inasmuch as key-controlled back spacing mechanisms are well-known, only a back spacing key 150 is shown in the drawings, and it is evident that this key is not depressible when the leftmost block 151 is crowded against the abutment 153 as when the front end of the lever 146 is depressed. Likewise, since tabulating mechanisms are also well-known in the art, it is deemed necessary to show and describe only such parts thereof as are more immediately associated with the locking mechanism 148, 151, 152, 153. It may, however, be said that the tabulating mechanism may be of the form shown and described in the patent to Helmond No. 2,303,878, dated December

1, 1942. From Fig. 1 it will be seen that a tabulator key 158, when operated, depresses a lever 151 extending transversely of the machine, about a pivot 158, so that its right end acts upon the front end of a lever 161 which, according to said above-mentioned application, when acted upon brings about a power tabulating operation. However, should said blocks 151, 152 be crowded together, as hereinbefore mentioned, the lever 161, and therefore also the key 157, will be locked against operation. Similarly, a tabulator stop-setting key 162 cannot be operated when said blocks 151, 152 are crowded, because a link 163, pendant from an arm 164 integral with the key, cannot enter between two of the blocks 151 immediately associated therewith. From the foregoing it is clear that no more than one of the keys 123, 150, 156, 162 may be depressed effectively at one time and that any of these keys, when operated, will cause the remainder, as well as the lever 146, to be locked against operation. The cage 154 includes a front, a rear, and a top wall, none shown, for retaining the blocks 151 and 152, clearances being provided for the various levers and the link 163 cooperating with the blocks 151, 152.

Upon operation of the carriage return key 123, the yoke 98 and its shaft 97 move to closed clutch position; and, for the purpose of maintaining the lever 146 operated during the carriage returns, independently of the release of the carriage return key 123, the right end of a link 165 connected to an arm 166 integral with the arm 161 assumes an elevated supporting position underneath a rearwardly extending arm 167 of the lever 146, thereby maintaining the front end of the lever 146 in block crowding, lowered position. As is seen in Fig. 1, the right end of the link 165 normally lies low in a vertical guide slot 168 provided in the right side wall 11 of the machine, but, incidental to the clutch closing operation, see Fig. 6, the link 165 will be cammed upwardly about its pivotal connection with the arm 166, by reason of a cam face 171 on the link.

The clutch 95, 96 may also be closed in response to the carriage reaching a line end position, in a manner not shown, by an automatic tripping operation of the latch 122. It will be seen that the link 165 in such an event displaces the arm 167 of the lever 146 upwardly, thereby causing the crowding of the blocks 151, 152 to lock the lugs 150, 156, 162. However, should the blocks, at the time the latch is automatically tripped, be crowded by reason of an operation of one of the keys 150, 156, 162, the link 165 will be stopped in its leftward movement because the arm 167 will not allow upward movement of the link as compelled by the face 171. Therefore, it is always necessary to release the keys 150, 156, 162 before an automatic carriage return operation can get under way.

It has been stated that the motor 86 rotates continuously. Likewise, the snatch roll 34 may rotate continuously and, to this end such roll may be driven by the spindle 91, through the medium of a belt drive, not shown.

Having the above-described locking and blocking mechanisms fully in mind, it will be seen that these mechanisms, although unfailing in their purposes, do not in the least impede or otherwise disturb the touch of the type keys 35, which, for this reason, can be operated with an undisturbed and even rhythm and, therefore, in more rapid succession and with less attendant fatigue to the

operator. On the other hand, such keys which are less frequently used, and operation of which under certain conditions might result in damage to the machine, are operable only when no damage can result. It will also be observed that only the typing mechanism is locked at line ends, leaving the operator the opportunity to operate any one of the keys 83, 123, 150 or 156.

Therefore, the carriage may be back spaced, 10 or the margin release key may be operated, in either case causing return of the slide 73 to non-blocking position. If the return of the carriage is in order, the carriage return key may be operated. However, it will be remembered, these keys 15 can be operated only one at a time.

Fig. 7 illustrates a modified mechanism where-in the elongate block 152 is replaced by additional small blocks or rolls 181 wherewith the type keys 35 may enter. The type keys just like the keys 150, 156, 162, therefore, may be depressed only one at a time, whereby clashing of the type bars is positively avoided since the operator is prevented from bringing about simultaneous, or to closely following operation of the type bars. This modified structure, however, affects the key touch unfavorably and is only desirable for typists who are inexperienced and incapable of rhythmically operating the machine. In conjunction with Fig. 7, it may further be stated that typing at line ends is reliably prevented through the actuator blocking member or slide 73.

What is claimed is:

1. In a power-driven typewriting machine having a frame, a carriage adapted to traverse said frame, and a multiplicity of operable type actions, the combination with power-drive means, of normally quiescent actuator means for each of said type actions, each actuator means being movable from a normal position into transitory motion-receiving association with said power-drive means and thereby being caused to execute a single type-action-operating cycle, at the end of which cycle the actuator means is in a normal position, means for selectively moving said actuator means into motion-receiving association with said power-drive means, a member operable for blocking all said actuator means against movement into said motion-receiving association but normally allowing said actuator means to be moved free thereof into said motion-receiving association, each of said actuator means including a part wherewith said member, when operated, cooperates to effect said blocking, said part of any of said actuating means being normally clear of the operating range of said member, and being unobstructing to the operation of said member during a late portion of each cycle, means to letter-feed said carriage during said late portion of each said cycles, and means to operate said member in response to a line-end letter-feeding movement.

2. In a power-driven typewriting machine having a frame, a carriage adapted to traverse said frame, a multiplicity of type actions, means to letter-feed the carriage in response to an operation of any type action, the combination with a power-drive element, of type action actuators movable into motion-receiving relation with said power-drive element, key means to move said actuators selectively into motion-receiving relation with said power-drive element, means to divorce automatically the actuators from the power-drive element and cause their return after they have received a typing impulse, said last

means providing for the return of said actuators free of said power-drive element, a member common to all said actuators, normally clear of the operating paths in which said actuators are movable into motion-receiving relation with said power-drive element, but operable so as to block said actuators against movement into motion-receiving relation with said power-drive element, and means including a margin stop to operate said member in response to a line-end letter-feeding movement of the carriage, said line-end letter-feeding movement occurring during the return of any actuator causing such movement, and said actuators, while returning, allowing operation of said member.

3. In a power-driven typewriting machine having a frame, a carriage adapted to traverse said frame, a multiplicity of type actions, means to letter-feed the carriage in response to an operation of any type action, the combination with a power-drive member, of type action actuators movable into motion-receiving relation with said power-drive member, key means to move said actuators selectively into motion-receiving relation with said power-drive member, means to automatically divorce the actuators from the power-drive member and cause their return after they have received a typing impulse, said last means providing for the return of said actuators free of said power-drive member, a toothed slide operable so that its teeth lock the actuators against movement into motion-receiving relation with said power-drive member, and means including a margin stop, to operate said slide in response to a line-end letter-feeding movement of the carriage, said line-end letter-feeding movement occurring during the return of any actuator causing such movement, and said actuators, while returning, allowing operation of said slide.

4. In a power-driven typewriting machine having a frame, a carriage adapted to traverse said frame, a multiplicity of operable type actions, and means to power-return said carriage, the combination with power-drive means, of normally quiescent actuator means for each of said type actions, each actuator means being movable from normal position into transitory motion-receiving association with said power-drive means and thereby being caused to execute a single type-action-operating cycle at the end of which cycle the operated actuator means is in a normal position, means including type-keys for selectively moving said actuator means into motion-receiving association with said power-drive means, a device operable for blocking all said actuator means against movement into said motion-receiving association but normally allowing said actuator means to be moved free thereof into said motion-receiving association, each of said actuator means including a part wherewith said device, when operated, cooperates to effect said blocking, said part of any of said actuating means being normally clear of the operating range of said device, and being unobstructing to the operation of said device during a late portion of each cycle, means to letter-feed said carriage during said late portion of each said cycle, means to operate said device in response to a line-end letter-feeding movement, other keys, normally ineffective key-locking means for said other keys, and means to render said device operated and to render said key-locking means effective during power-returns of the carriage.

5. In a power-driven typewriting machine having a frame, a carriage adapted to traverse said

frame, a multiplicity of type actions, means to letter-feed the carriage in response to an operation of any type action, the combination with a power-drive means, of type action actuators movable into motion-receiving relation with said power-drive means, means including type-keys to move said actuators selectively into motion-receiving relation with said power-drive member, means to automatically divorce the actuators from the power-drive member and cause their return after they have received a typing impulse, said last means providing for the return of said actuators free of said power-drive member, a member common to all said actuators, normally clear of the operating paths in which said actuators are movable into motion-receiving relation with said power-drive means, but operable so as to block said actuators against movement into motion-receiving relation with said power-drive member, and means including a margin stop to operate said member in response to a line-end letter-feeding movement of the carriage, operable elements including a plurality of keys other than type-keys, locking means effective upon operation of any one of said elements to lock the remainder of said elements against operation, and means to render said member and one of said elements operated whenever the carriage is being power-returned.

6. In a power-driven typewriting machine having a frame, a carriage adapted to traverse said frame, a multiplicity of operable type actions, and means to power-return said carriage, the combination with power-drive means, of normally quiescent actuator means for each of said type actions, each actuator means being movable from a normal position into transitory motion-receiving association with said power-drive means and thereby being caused to execute a single type-action-operating cycle at the end of which the operated actuator means is in a normal position, means including type-keys for selectively moving said actuator means into motion-receiving association with said power-drive means, a device operable for blocking all said actuator means against movement into said motion-receiving association but normally allowing said actuator means to be moved free thereof into said motion-receiving association, each of said actuator means including a part wherewith said device, when operated, cooperates to effect said blocking, said part of any of said actuating means being normally clear of the operating range of said device, and being unobstructing to the operation of said device during a late portion of each cycle, means to letter-feed said carriage during said late portion of each said cycle, means to operate said device in response to a line-end letter-feeding movement, operable elements including a plurality of other keys, locking means effective upon operation of any one of said elements to lock the remainder of said elements against operation, and means to render said device and one of said elements operated for the duration of every power-return of the carriage.

7. In a power-driven typewriting machine having a frame, a carriage adapted to traverse said frame, a multiplicity of type actions, a carriage-return key, a power-carriage-return mechanism, and means responsive to the operation of said key to cause said mechanism to return said carriage to a predetermined position, the combination of an actuating mechanism for each type action, a common power-drive member for said actuator mechanisms, each actuator mech-

anism adapted in consequence of a transitory engagement with said power-drive member to execute a type-action-operating cycle, a normally ineffective device operable to block all said actuating mechanisms against engagement with said power-drive member, means including type-keys to effect transitory engagement of said actuator mechanisms selectively, keys other than type-keys including a margin release key and a back-spacing key, locking means effective upon operation of said carriage-return key or any one of the said other keys to lock the remainder of these keys against operation, and means for rendering said device effective in response to a line-end letter-feeding movement, wherefore after such movement all said type-keys are blocked against operation and wherefore said other keys may then be operated, but only one at a time.

8. In a power-driven typewriting machine having a frame, a carriage adapted to traverse said frame, a multiplicity of type actions, a carriage-return key, a power-carriage-return mechanism, and means responsive to the operation of said key to cause said mechanism to return said carriage to a predetermined position, the combination of an actuating mechanism for each type action, a common power-drive member for said actuator mechanisms, each actuator mechanism adapted in consequence of a transitory engagement with said power-drive member to execute a type-action-operating cycle, a normally ineffective device operable to block all said actuating mechanisms against engagement with said power-drive member, means including type-keys to effect transitory engagement of said actuator mechanisms selectively, other keys, locking means effective upon operation of said carriage-return key or any one of the said other keys to lock the remainder of these keys against operation, said locking means including an element operable by said carriage-return key, said element, when operated, causing said locking means to be effective with respect to all the said other keys, means to cause said responsive means to hold said element operated during the return of the carriage and means for operating said device for the duration of every power-carriage return.

9. In a power-driven typewriting machine having a frame, a carriage adapted to traverse said frame, a multiplicity of operable type actions, and means to power-return said carriage, the combination with power-drive means, or normally quiescent actuator means for each of said type actions, each actuator means being movable from a normal position into transitory mo-

tion-receiving association with said power-drive means and thereby being caused to execute a single type-action-operating cycle at the end of which cycle the operated actuator means is in a normal position, means including type-keys for selectively moving said actuator means into motion-receiving association with said power-drive means, a device operable for blocking all said actuator means against movement into said motion-receiving association but normally allowing said actuator means to be moved free thereof into said motion-receiving association, each of said actuator means including a part where-with said device, when operated, cooperates to effect said blocking, said part of any of said actuating means being normally clear of the operating range of said device, and being unobstructing to the operation of said device during a late portion of each cycle, means to letter-feed said carriage during said late portion of each said cycle, means to operate said device in response to a line-end letter-feeding movement, keys other than type-keys, locking means effective upon operation of any one of the aforesaid keys, to lock the other keys against operation, said locking means including an element which by movement to an operated position will render said locking means effective with respect to all said keys, and means for causing said element to occupy said operated position whenever the carriage is being power-returned.

10. In a power-driven typewriting machine having a frame, a carriage adapted to traverse said frame, a multiplicity of type actions, means to letter-feed said carriage in consequence of an operation of any type action, means to power-return said carriage, the combination of a power-drive member, normally quiescent actuator means individual to said type actions, each actuator means being adapted to be coupled transitorily to said power-drive member and being adapted in consequence thereof to execute a type-action-actuating cycle, means including type keys to couple transitorily said actuating means selectively with said power-drive member, a toothed slide operable so that its teeth are adapted to block coupling of all said actuator means with said power drive member, means to operate said slide in response to a line-end and letter-feeding movement of the carriage, other keys, normally ineffective key-locking means for said other keys, and means to cause said last means to be effective and said slide to be operated when said power-carriage return means is active.

HARRY C. YAEGER.
